UNITED STATES PATENT OFFICE.

JOHN RYCKMAN, OF MINNEAPOLIS, MINNESOTA.

HEATING APPARATUS.

1,338,965.

Specification of Letters Patent.

Patented May 4, 1920.

Application filed April 6, 1918. Serial No. 227,081.

To all whom it may concern:

Be it known that I, JOHN RYCKMAN, a citizen of the United States, residing at Minneapolis, in the county of Hennepin and 5 State of Minnesota, have invented certain new and useful Improvements in Heating Apparatus, of which the following is a specification.

My invention relates to heating apparatus 10 and the object is to provide a system in which a circulation of hot water or steam for heating purposes may be obtained by the combustion of fuel oil in an efficient and economical manner.

15 The full objects and advantages of my invention will appear in connection with the detailed description thereof and are particularly pointed out in the claims.

Referring to the drawings which illustrate the application of my invention in one form,—

Figure 1 is a diagrammatic view, largely in vertical section, of my apparatus. Fig. 2 is a view in section on line 2—2 of Fig. 1.

25 Referring to the drawings, 10 indicates the water jacket of the boiler having the inner cylindrical wall 12 and the outer cylindrical wall 14, these two walls being joined at their ends to form an annular

30 chamber for containing water. Leading from the top of the water jacket thus formed is the outlet pipe 16 while a return pipe 18 enters the bottom of the water jacket. Inclosing the water jacket is the

35 drum 20, preferably of sheet metal, from the upper end of which is led the escape flue 22 for spent gases. The rear end of the drum extends beyond the water jacket to form a passageway 24 and the drum is

40 positioned eccentrically around the water jacket with their lower surfaces in contact so as to form the passageway 26 at the top. The boiler formed by this construction may be supported on suitable legs 28 connected

45 by cross bars 30. The front end of the drum fits closely upon the front end of the water jacket and is provided with a clean out door 32 above the water jacket and the opening 34 leading to the space within the

50 inner wall 12 of the water jacket. A tube 36 having a burner tip 38 extends through the opening 34 for a short distance and beyond the burner tip is a deflector 40. The pipe 36 leads from a fuel oil tank 42, and

within the tank the pipe is bent to form 55 two vertical portions 44 and 46 connected by a short bend at their lower ends. The portion 44 is closed at its top and at a short distance below the top is provided with an opening 48 for entrance of the compressed 60 air, while in the bottom of the portion 46 is a small opening 50 for entrance of fuel oil. The valve 52 controls the flow through the pipe 36. The tank 42 is provided with a cock 54 which is ordinarily closed but 65 which may be opened to determine the upper level of the fuel oil in the tank when the oil is supplied by opening the valve 56 in the supply pipe 58. The space in the tank 42 above the oil level is supplied with 70 compressed air from a storage tank 60 connected with the top of tank 42 by a pipe 62 provided with an air regulator 64 and a pressure gage 66. The storage tank is connected by a pipe 68 with an air compressor 75 70. The pipe 68 is provided with a pressure gage 72 and with an automatic electric regulator 74 of well known construction. An electric motor 76 is geared to the air compressor and a supply of current to the 80 motor is switched on and off by the regulator according to the air pressure in the pipe 68.

The advantages and operation of my invention will be apparent from the foregoing 85 description. A substantially constant air pressure is maintained in the compressed air storage tank and pressure therefrom reduced, as desired, by the air regulator 64 is transmitted to the space at the top of the 90 fuel oil reservoir. Notwithstanding slight fluctuations in the air pressure in the storage tank, it will be apparent that a constant pressure will be maintained in the tank 14. Compressed air enters the opening 48 and 95 flows through the pipe 36 to the burner in its passage drawing in fuel oil in small quantities through the small opening 50. Air and oil are delivered from the burner tip in the form of a fine mist or spray which 100 burns with intense heat in the space within the inner wall of the water jacket, the burning gases being deflected against the inner wall 12 by the deflector and passing back over the outer wall 14 to the escape flue 22. 105 The water in the water jacket will be quickly heated and cause a circulation of hot water out through the pipe 16 and returning

through the pipe 18. It is obvious that my apparatus may be used for supplying steam instead of hot water, if desired.

I claim:

- 5 1. A heating apparatus comprising a fuel oil tank, a compressed air tank, a pipe connecting said air tank to the top of said oil tank, an air compressor connected with said air tank, an electric motor operatively connected with said air compressor, a regulator for switching on and off the supply of current to said motor according to the pressure on said air tank, a burner and means for delivering oil and air from said oil tank
- 10 15 through said burner in the form of mist.

2. A heating apparatus comprising a burner, a fuel oil tank, a compressed air tank, a pipe connecting said air tank to the top of said oil tank, a U-shaped pipe in said oil tank, one of the branches of said U-shaped pipe being closed at its top except for a small air inlet opening, the other branch of said U-shaped pipe having a small oil inlet near its bottom and having its upper end connected to said burner for delivering oil and air from said oil tank through said burner in the form of mist.

In testimony whereof I hereunto affix my signature.

JOHN RYCKMAN.
